UNITED STATES PATENT OFFICE.

FRANK J. LIEBER, OF HAWLEY, PENNSYLVANIA.

DESIGN FOR A PLUMBER'S TOOL.

SPECIFICATION forming part of Design No. 30,486, dated April 4, 1899.

Application filed March 7, 1899. Serial No. 708,145. Term of patent 7 years.

To all whom it may concern:

Be it known that I, FRANK J. LIEBER, a citizen of the United States, residing at Hawley, in the county of Wayne and State of Pennsylvania, have invented and produced a new and original Design for Plumbers' Tools, of which the following is a specification, reference being had to the accompanying drawings, forming part thereof.

10 In the drawings hereunto annexed, Figure 1 is a perspective view showing my design, and Fig. 2 is a plan view.

As shown in the drawings, the design consists of a major portion *a*, which is substantially heart-shaped, the sides *b* and *c*, however, being straight and meeting at an acute angle *d*. At the upper edge *e* of the major portion the material of which the blank is formed is curved over to lie upon the face of the major portion, and it is substantially square in outline, as shown in Fig. 2. Extending upwardly from the square portion *f* and at right angles to the face of the major portion *a* is a minor heart-shaped portion *g*,

with its apex *h* upward and having its edges 25 curved in the direction of the edge *e* of the major portion. The axis of curvature of one edge *i* of the minor portion, however, extends across the upper portion of the other edge *k*, so that the resultant cone-section *l* has its apex 30 within the edge *k*, the apex of the minor portion *g* extending thereabove and giving said minor portion a general convolute appearance.

The leading features of my design are the 35 heart-shaped major portion having straight edges converging to a point and the heart-shaped minor portion having a convolute appearance with the straight edge *i*.

Having thus described my invention, what 40 I claim as new, and desire to secure by Letters Patent of the United States, is—

The design for a plumber's tool, substantially as herein shown and described.

FRANK J. LIEBER.
